BOTTLE AND LIKE CRATE

Arnold T. Faulkner, Battle Creek, Mich., assignor to United Steel and Wire Company, Battle Creek, Mich., a corporation of Michigan

Application September 20, 1939, Serial No. 295,698

14 Claims. (Cl. 220—19)

This invention relates to improvements in bottle and like crates.

The main objects of this invention are:

First, to provide a bottle or like crate in which the parts most likely to be injured in use are so constructed and assembled with the coacting parts that they may be easily renewed by relatively unskilled workmen.

Second, to provide a crate bottom unit or assembly which may be furnished to the user as a separate element to be installed by the user as a substitute for the bottom with which the crate was originally provided.

Third, to provide a partition unit for bottle crates which may be assembled as a unit and easily installed either at the factory or furnished as a separate unit to be installed in making repairs to a damaged crate.

Fourth, to provide a structure having these advantages in which the parts are economical to produce and assemble and at the same time are strong and rigid when assembled.

Objects relating to details and economies of the invention will appear from the description to follow. The invention is defined and pointed out in the claims.

A preferred embodiment of the invention is illustrated in the accompanying drawings, in which:

Fig. 1 is a perspective view of a bottle crate embodying the features of my invention.

Fig. 2 is a plan view of the assembled bottom unit.

Fig. 3 is an enlarged fragmentary vertical section on line 3—3 of Fig. 5.

Fig. 4 is a horizontal section on line 4—4 of Fig. 5 illustrating certain of the steps in assembling a bottom unit with the frame and side wall portions of a crate.

Fig. 5 is a fragmentary view in section on line 5—5 of Fig. 4 illustrating certain steps in the assembling of one of the partition members.

Fig. 6 is a side elevation of a modified form or embodiment of the invention, the modification being particularly in the matter of anchoring the bottom.

Fig. 7 is an enlarged fragmentary perspective view of the embodiment shown in Fig. 6.

My improvements are particularly adapted for the type of bottle crate illustrated in Patent 1,690,418 issued November 6, 1928, to L. W. Macomber in which the various parts entering into the crate are formed of wire or stock of suitable gauge and secured together by welding. In commercial use, these crates are subject to severe

use and frequently careless handling with a result that the bottoms are broken or rendered useless, sometimes the partition members forming the bottle compartments. In this structure 5 of the Macomber patent, these parts are welded in position and to replace them or repair a crate of this character it is necessary to return the crate to the factory. In view of the fact that the crates are not designed to be nested the expense of returning them to the factory plus the cost of repair is frequently prohibitive.

The main feature of my present invention is to provide a structure in which the bottom and partition members are assembled as units and can 15 be readily removed for purposes of repair and other units substituted, this work being done by unskilled workmen and without necessitating return of the crates to the factory and, further, my improvements provide a structure which permits the very rapid and economical manufacture of the units and their assembly as a factory or manufacturing advantage.

The embodiment of my invention illustrated 20 comprises a bottom frame 1, top frame 2, and vertically spaced intermediate frames 3, 3. These frames are continuous, being formed of heavy wire or light rod stock of suitable gauge conformed and the ends of the stock being welded together. Upright slats or side and end wall members 4 are welded preferably to the inner sides of these frame members.

Corner members 5 of somewhat heavier stock 25 are provided, these corner members being arranged in downwardly diverging relation and preferably formed of loops of wire, the eight ends 6 extending above the top frame to provide stacking lugs—that is, these lugs are engageable within the bottom frame of a superimposed crate for holding the crates in stack position or alignment. These corner members 5 preferably have inwardly inclined portions 7 at their lower ends, these portions being below the bottom intermediate frame member 3, see Fig. 3. This serves two functions—one is that it spaces the top and 30 intermediate members inwardly relative to the bottom frame member so that clearance is provided when the crates are arranged side by side with the bottom frames in contact, and second, both the downwardly diverging feature and these inclined portions 7 serve additional functions in the assembling and fixedly securing of the bottom in position.

The assembled bottom unit comprises two sets 35 of bottom members designated by the numerals 8 and 9, in the embodiment illustrated the set

8 being the longitudinal members and the set 9 the transverse members. However, it will be understood that these crates are sometimes square and that the terms longitudinal and transverse are only used as a matter of convenience in describing the parts. These sets of bottom members are arranged in crossed relation and welded at their crossing points as indicated at 10, see Fig. 5. The bottom members terminate in eyes 11 which extend beyond the uprights sufficiently to receive the tie or retaining rods 12.

The bottom assembled unit is inserted with its members above and resting upon the bottom frame and preferably in a somewhat elevated position as indicated by dotted lines at 13 in Fig. 3. The retaining rods 12 are then inserted through the eyes. These retaining rods 12 are formed with loops 14 at one end and they are inserted to bring their loops into engagement with one of the upright corner members, the other end 15 of the retaining member projecting beyond the other corner member for that side of the crate. By reference to Fig. 3, it will be noted that in this elevated position at 13 the retaining rod does not contact the upright members so that the rod may be easily inserted. After they are inserted, they are pushed downwardly as shown by full lines in Fig. 3 which brings the retaining rods into engagement with the uprights thereby firmly anchoring the bottom unit against lateral movement. In this position, the second hook or loop indicated at 16 in Fig. 4 is bent around the adjacent corner upright, thus locking the rods in position. The upwardly inclined relation of the corner members prevents these hooks or loops of the retaining rods from sliding upward on the members with which they are engaged and the bottom is thus effectively anchored in position.

The partition members comprise sets of parallel spaced members 17 and 18 disposed in crossed relation and welded to each other at their crossing points as indicated at 19. These members terminate in downwardly facing loops 20 adapted to be hooked over the intermediate frame members as shown by full lines in Fig. 5 and clamped therearound as shown by dotted lines at 21, Fig. 5. These loops 20 are upwardly offset providing shoulders at 22 which engage the frame members and effectively anchor the partition units against lateral movement and, further, this upward offset has the advantage of enabling effective engagement of a tool with the loops for closing them around the frame members. This work may be done with the common type of pliers if desired.

The pair of partition units coact to provide bottle compartments or cells, the structure illustrated being designed to receive twelve bottles. The longitudinal members 8 of the bottom are preferably disposed in spaced pairs positioned centrally relative to the compartment—that is, a row of compartments so that a bottle arranged in the compartment is evenly supported by a pair of the bottom members.

These bottom members and partition units may be very economically manufactured, the welding operations being simple and they can be rapidly assembled with the wall or body portion of the crate. In the event of damage to the bottom or partition unit such as to render repair necessary or advisable, the units may be readily disassembled and replaced by new units. In the event it is desired to repair a crate of the type shown in the Macomber patent in which the partition and bottom members are welded in place, these

members can be pried or knocked off at their welding points and the bottom and partition described assembled with the body portion of the crate and this may be done, as pointed out by persons of little mechanical skill or experience.

In the embodiment of my invention shown in Figs. 6 and 7, the outer longitudinal members of the bottom designated 81 are provided with outwardly turned arms or end portions 82 terminating in eyes 11. This arrangement leaves the corners of the crate free from obstruction to receive the positioning lugs 6 when the crates are stacked. In this embodiment, the retaining rods 121 corresponding to the rods 12 of the embodiment heretofore described terminate at at least one end in upwardly turned arms 122 having downwardly facing loops 123 at the ends thereof engaging the intermediate frame member 3. The bottom is positioned and the retaining rods inserted and the loops 123 engaged over or formed around the intermediate frame members, thus not only locking the bottoms in position but preventing upward movement thereof.

I have illustrated and described my improvements as embodied in a milk bottle crate. I have not illustrated my improvements in other embodiments or adaptations which I contemplate as it is believed that this disclosure will enable those skilled in the art to embody or adapt my improvements as may be desired.

Having thus described my invention, what I claim as new and desire to secure by Letters Patent is:

1. In a bottle crate, the combination of bottom, top and vertically spaced intermediate frame members, upright side and end members welded to the inner sides of said frame members, including downwardly diverging corner members disposed at the corners of the crate and welded to the inner sides of said frame members, the portions of said corner members below the bottom intermediate frame member being inclined outwardly, a bottom unit fixedly associated with said frame and upright members comprising sets of spaced parallel members disposed in crossed relation and welded together at their crossing points and disposed above and resting upon said bottom frame member, said bottom members extending from the interior of the crate outwardly and terminating in eyes disposed outwardly beyond said upright members, individual retaining rods arranged through said eyes on the outer sides of said upright members and having retaining members at the ends thereof engageable with certain of said upright members, the diverging relation of said corner members acting to prevent upward movement of said retaining rods engaged therewith, and vertically spaced partition units disposed interiorly of the crate, each comprising sets of spaced parallel members disposed in crossed relation and welded together at their crossing points, the ends of said partition members terminating in loops engaged with and closed upon the intermediate frame members, said partition units coacting to provide a plurality of bottle receiving compartments.

2. In a bottle crate, the combination of bottom, top and vertically spaced intermediate frame members, upright side and end members welded to the inner sides of said frame members, including corner members disposed at the corners of the crate and welded to the inner sides of said frame members, a bottom unit fixedly associated with said frame and upright members comprising sets of spaced parallel members disposed in

crossed relation and welded together at their crossing points and disposed above and resting upon said bottom frame member, said bottom members extending from the interior of the crate outwardly and terminating in eyes disposed outwardly beyond said upright members, individual retaining rods arranged through said eyes on the outer sides of said upright members and having retaining members at the ends thereof engageable with certain of said upright members, and vertically spaced partition units disposed interiorly of the crate, each comprising sets of spaced parallel members disposed in crossed relation and welded together at their crossing points, the ends of said partition members terminating in loops engaged with and closed upon the intermediate frame members, said partition units coacting to provide a plurality of bottle receiving compartments.

3. In a bottle crate, the combination of bottom, top and vertically spaced intermediate frame members, upright side and end members welded to the inner sides of said frame members, including corner members disposed at the corners of the crate and welded to the inner sides of said frame members, a bottom unit fixedly associated with said frame and upright members comprising sets of spaced parallel members disposed in crossed relation and welded together at their crossing points and disposed above and resting upon said bottom frame member, said bottom members extending from the interior of the crate outwardly and terminating in eyes disposed outwardly beyond said upright members, individual retaining rods arranged through said eyes on the outer sides of said upright members and having retaining members at the ends thereof engageable with certain of said upright members, and vertically spaced partition units disposed interiorly of the crate, each comprising sets of spaced parallel members disposed in crossed relation and welded together at their crossing points, the ends of said partition members terminating in loops engaged with and closed upon the intermediate frame members, said partition units coacting to provide a plurality of bottle receiving compartments, the upper set of bottom members being arranged in pairs positioned centrally relative to said compartments.

4. In a crate, the combination of frame members, upright side and end members welded to the inner sides of said frame members, including downwardly diverging corner members disposed at the corners of the crate and welded to the inner sides of said frame members, the portions of said corner members below the intermediate frame member being inclined outwardly, a horizontal unit fixedly associated with said frame and upright members comprising sets of spaced parallel members disposed in crossed relation and welded together at their crossing points and disposed above and supported by a frame member, said horizontal unit members extending from the interior of the crate outwardly and terminating in eyes disposed outwardly beyond said upright members, and individual retaining rods arranged through said eyes on the outer sides of said upright members and having loops at the ends thereof engaging said corner members, the diverging relation of said corner members acting to prevent upward movement of said retaining rods engaged therewith.

5. In a crate, the combination of frame members, upright side and end members welded to the inner sides of said frame members, including

downwardly diverging members welded to the inner sides of said frame members, a horizontal unit fixedly associated with said frame and upright members comprising sets of spaced parallel members disposed in crossed relation and welded together at their crossing points and disposed above and supported by a frame member, said horizontal unit members extending from the interior of the crate outwardly and terminating in eyes disposed outwardly beyond said upright members, and individual retaining rods arranged through said eyes on the outer sides of said upright members and having retaining loops at the ends thereof engageable with said downwardly diverging members, the diverging relation of said members acting to prevent upward movement of said retaining rods engaged therewith.

6. In a crate, the combination of frame members, upright side and end members welded to said frame members including corner members disposed at the corners of the crate and welded to said frame members, a horizontal unit fixedly associated with said frame and upright members comprising sets of spaced parallel members disposed in crossed relation and welded together at their crossing points and disposed above and supported by a frame member, said horizontal unit members extending from the interior of the crate outwardly and terminating in eyes disposed outwardly beyond said upright members, and individual retaining rods arranged through said eyes on the outer sides of said upright members and having loops at the ends thereof engaging certain of said upright members.

7. In a crate, the combination of frame members, upright side and end members welded to said frame members, including corner members disposed at the corners of the crate and welded to said frame members, the portions of said corner members below the intermediate frame member being inclined inwardly, a horizontal unit fixedly associated with said frame and upright members comprising sets of spaced parallel members disposed in crossed relation and welded together at their crossing points and disposed above and supported by a frame member, said horizontal unit members extending from the interior of the crate outwardly and terminating in eyes disposed outwardly beyond said upright members, and individual retaining rods arranged through said eyes on the outer sides of said upright members and having loops at the ends thereof engaging certain of said upright members.

8. In a bottle crate, the combination of bottom, top and vertically spaced intermediate frame members, upright members welded to said frame members, a bottom unit comprising sets of spaced members disposed in crossed relation and secured together at their crossing points, said bottom members extending from the interior of the crate outwardly and terminating in eyes disposed outwardly beyond said upright members, individual retaining rods arranged through said eyes on the outer sides of said upright members and having retaining loops at the ends thereof, and vertically spaced partition units disposed interiorly of the crate, each comprising sets of spaced parallel members disposed in crossed relation and welded together at their crossing points, the ends of said partition members terminating in downwardly facing upwardly offset loops engaged with and closed upon the intermediate frame members, said partition units coacting to provide a plurality of bottle receiving compartments, the upper set of bottom members being arranged in

pairs positioned centrally to said compartments.

9. In a bottle crate, the combination of bottom, top and intermediate frame members, upright members welded to said frame members, a bottom unit comprising sets of spaced members disposed in crossed relation and secured together at their crossing points, said bottom members extending from the interior of the crate outwardly and terminating in eyes disposed outwardly beyond said upright members, individual retaining rods arranged through said eyes on the outer sides of said upright members and having loops at the ends thereof engaged with certain of the upright members, and a partition unit disposed interiorly of the crate comprising sets of spaced parallel members disposed in crossed relation and welded together at their crossing points, the ends of said partition members terminating in loops engaged with and closed upon the intermediate frame member.

10. In a bottle crate, the combination of bottom and top frame members, upright members welded to said frame members, a horizontal unit comprising sets of spaced members disposed in crossed relation and secured together at their crossing points, said members extending from the interior of the crate outwardly and terminating in eyes disposed outwardly beyond said upright members, and individual retaining rods arranged through said eyes on the outer sides of said upright members and having loops at the ends thereof engaged with certain of the upright members.

11. In a bottle crate, the combination of bottom and top frame members, upright members secured to said frame members, a horizontal unit comprising sets of spaced members disposed in crossed relation and secured together at their crossing points, said members extending from

the interior of the crate outwardly and terminating in eyes disposed outwardly beyond said upright members, and individual retaining rods arranged through said eyes on the outer sides of said upright members and in contact therewith and having retaining loops at the ends thereof.

12. A crate comprising top, bottom, and an intermediate frame member, uprights secured thereto, a bottom unit comprising sets of spaced members disposed in crossed relation and secured together at their crossing points, said bottom members extending from the interior of the crate outwardly and terminating in eyes disposed outwardly beyond said upright members, and retaining rods arranged through said eyes on the outer side of said upright members and in contact therewith and having upwardly offset ends terminating in loops engaged with said intermediate frame member.

20 13. A crate comprising top, bottom, and an intermediate frame member, uprights secured thereto, a bottom unit comprising sets of spaced members disposed in crossed relation and secured together at their crossing points, said bottom members terminating in eyes extending outwardly beyond said upright members, and retaining rods arranged through said eyes on the outer side of said upright members and in contact therewith and having retaining engagement with said intermediate frame member.

25 14. A crate comprising top, bottom, and an intermediate frame, uprights secured thereto, a bottom unit comprising sets of spaced members disposed in crossed relation and secured together at their crossing points, said bottom members terminating in eyes, and retaining rods arranged through said eyes and having retaining engagement with said intermediate frame.

ARNOLD T. FAULKNER.
